FURNITURE SEAT

Luther D. Lichty, Reading, Pa., assignor to
 Duplex Swing-Spring Seat Company, Inc.,
 Reading, Pa., a corporation of Pennsylvania

Application February 25, 1931. Serial No. 518,076

8 Claims. (Cl. 155—179)

The invention relates to furniture seats, and more particularly to a construction of the frame of the article of furniture and the arrangement of the seat springs by which the seat as a whole will possess greater resiliency toward the back 5 of the article of furniture and thus afford greater comfort to the user thereof.

Heretofore, in the construction of chairs, sofas and settees, it has been the practice to provide a 10 seat frame in which all of the rails are horizontally arranged the same distance from the floor or from the bottom of the chair, sofa or settee legs. In producing some types of lounging chairs, it has sometimes been the practice to make the 15 rear legs shorter than the front legs so as to give a downward tilt to the chair and the chair seat toward the back of the chair.

In such chairs, the universal practice has been to support ordinary seat springs from means secured to the bottom of the frame rails, said supporting means ordinarily being burlap strips interlaced with each other and secured by nails to said rails. It has also been the practice to place 20 all of said springs under compression by means of tie cords firmly secured to the tops of the different springs and to the tops of the frame rails, all of said springs being similarly tensioned so as to bring the top of the spring rigging parallel with the frame rails. With this 25 construction of furniture, the tendency is for the seat to sag centrally thereof after use, due mainly to the fact that the stretch of the burlap occurs centrally of the seat of the chair, or at points well away from the frame rails, which 30 stretch, when it becomes permanent, permits expansion of the springs grouped about the central portion of the seat resulting in increased resiliency at this point, or permit the springs, in their entirety, to drop sufficiently to give the 35 40 sagging effect above referred to.

With the construction of seat above referred to, the springs adjacent the back, front and side rails of the frame always possess less resiliency than the springs toward the center of 45 the seat so that there is a tendency to throw the occupant forwardly rather than backwardly.

With the above condition in mind, I have provided a furniture seat wherein the construction and arrangement of the seat springs is such as 50 to avoid the central sagging of the seat, and to tend under all conditions, to throw the occupant toward the back of the article into a comfortable posture.

With the construction of seat in accordance 55 with my invention, the legs of the article all

extend substantially plumb. Notwithstanding the tilting effect upon the occupant of the article, the top of the seat will at all times be substantially horizontal. In securing the desired results, I provide the various seat springs 60 with a non-flexible and non-elastic support, which support is maintained at an angle to the horizontal with a downward and rearward pitch, thus affording increased distance between the support for the bottom of the springs and the 65 top of the chair seat so as to permit the installation of compressed springs of different lengths from adjacent the front to adjacent the back of a chair. The inclination of the support for the springs results, when the tops of the springs 70 are brought to the desired horizontal level by means of the ordinary tie cords, in a seat structure in which the springs are of progressively increasing resiliency from adjacent the front toward the back of the chair. If desired, the supports for the springs may themselves be partially or wholly retained in relation to the front and back frame rails by a spring rigging which will take up the load upon the article when the seat springs have been compressed to develop a 80 tension in excess of that of the springs of the said spring rigging.

A spring seat embodying the invention may be produced without any material change in existing factory conditions or factory practices. 85

The invention consists primarily in a furniture seat embodying therein the combination with the frame of an article of furniture, of upholstery spring supporting means downwardly inclined from adjacent the front to adjacent the 90 back of the frame, a plurality of upholstery springs carried by said spring supporting means, and means tensioning said springs and bringing the tops thereof to a substantially horizontal plane, whereby said springs, from adjacent the 95 front to adjacent the back of the seat, will be of progressively lower tension; and in such other novel features of construction and combination of parts as are hereinafter set forth and described, and more particularly pointed out in 100 the claims hereto appended.

Referring to the drawing,

Fig. 1 is a front view in perspective of a sofa, the seat of which embodies the invention;

Fig. 2 is a sectional condensed view of a seat 105 structure fore and aft of the article of furniture in which the upholstery springs supporting members are sustained by expansion springs at the back and at the front thereof;

Fig. 3 is a view similar to Fig. 2 in which the 110

upholstery springs supporting member is pivotally supported from the front rail and suspended from the back rail by means of suspension springs; and

5 Fig. 4 is a detail view of the manner of pivotally supporting the upholstery springs supporting member from the front rail.

Like numerals refer to like parts throughout the several views.

10 In the embodiment of the invention shown in the drawing, the framework including the legs 10 is of the usual construction and arrangement. The front seat rail 11 is secured to the front legs in the usual manner and in the usual position. The back seat rail 12, while attached to the rear legs in the usual manner, is set upon a horizontal plane lower than that of the front rail 11. The side rails 13 are so mitred at the ends that the ends thereof coincide with both 15 the front rail 11 and the back rail 12 and yet have the side rails butt against the inner face of both the front and back legs of the article of furniture.

20 The back, front and side rails have their tops positioned well below the top plane of the seat structure, thus providing a point of attachment for the upholstery spring tie cords well below the tops of these springs. This arrangement greatly facilitates the tensioning of the springs during 25 the assembly of the seat structure. The arrangement of rails also conceals the upholstery spring supporting means. The position of the rear rail below the front rail gives that downward and rearward inclination to the spring supporting 30 members which develops those conditions in the seat structure hereinafter referred to.

35 I prefer to employ rigid, flexibly supported upholstery spring supporting means, and such are shown in the drawing.

40 In Figs. 1 and 2, the upholstery spring supporting means are shown as consisting of wooden slats 14 carrying at the opposite ends thereof metal fittings 15, co-operating with which are expansible suspension springs 16, the upper ends 45 of which are connected with metal fittings 17 secured to the front and back rails 11 and 12 respectively. The springs 16 hang substantially vertically so as to give a full floating effect to the upholstery spring supporting slat.

50 The number and spacing of the said slats 14 may vary with different manufacturers. Since the metal fittings 17 are supported respectively from the front and back rails 11 and 12, and since the springs 16 are of the same length and of substantially the same tension, it is obvious that the slats 14 or other rigid upholstery spring supporting means will extend at a downward angle from front to back of the seat as determined by the difference in the horizontal position of the 55 front and back rails. This difference may vary, although a drop of from one and one-half to two inches has been found highly desirable in actual practice.

60 Mounted upon each slat 14 or other spring supporting means is a row of upholstery springs 18, each of which springs, prior to its assembly in the seat structure, is like every other spring. Said springs 18 may be attached to the slats or other supporting means in any desired manner, and after the supporting means with the springs are secured in relation to the seat frame, tie cords, to firmly hold these springs in their desired position in the seat structure, are connected to the tops of adjacent springs in the usual manner and then secured to the tops of the front,

back and side rails so as to both stay the springs and place them under the desired compression.

When so tying in the springs each spring is brought with its top upon a substantially horizontal plane, so that the tying in of the springs results in the compression of those springs closely adjacent the front rail 11 to the maximum extent desired to secure the desired seat level, and a progressively lower compression of the springs toward the back of the seat.

80 The result is that the seat is progressively more resilient toward the back thereof because of the graduation of the degree of compression of the springs from the front toward the back of the seat. The top of the seat, however, is upon a substantially horizontal plane so as to preserve the desired appearance of the seat.

85 The degree of compression of the springs 18 from front to back is determined by the rearward and downward pitch of the spring supporting means.

90 In the drawing, the tie cords are shown at 19.

95 In Fig. 3 of the drawing, I have illustrated the invention as applied to a type of upholstery spring supporting means in which slats 20 are hinged at their forward ends to the front rail 11, and are suspended at their rear ends by means of fittings 15, springs 16 and fittings 17, as in the embodiment of the invention shown in Figs. 1 and 2. This construction ensures the maintenance of the front ends of the spring supporting means always upon the same level.

100 I employ a novel fitting pivotally connecting the spring supporting means 20 with the front rail 11 consisting of a sheet metal plate 21 adapted to be attached to the rear face of the rail 11. This plate has formed integrally therewith a central tongue 22 adapted to pass under and engage the lower edge of this rail and with an oppositely projecting flange 23 having rectangular openings 24 formed therein. The end of this flange 23 is turned downwardly as shown.

105 Carried by the slat 20 is a metal fitting 25 adapted to be connected with the under side of the slat and having an upturned tongue 26 adapted to engage the end of the slat. Upon opposite sides of the tongue 26, the fitting 25 is provided with arcuate tongues 27 adapted to pass through the slots 24 and pass below and across the flange 23. I employ the above construction because it facilitates the assembling of the slats in the seat structure and at the same time avoids any possibility of the slats becoming disengaged from the rail fitting.

110 A furniture seat embodying the invention is characterized by the following conditions:

115 When the article, such as a chair, is not in use, the seat has all of the appearances of an ordinary seat, all of the springs being expanded to the maximum extent allowed by the tie cords. As shown in Figs. 2 and 3 of the drawing, the springs toward the back of the seat will be of progressively increasing lengths because of the rearward and downward inclination of the supporting means for these springs.

120 Since all of the springs used in the seat were originally of the same dimensions, as to length as well as the material of which the springs are made, it is obvious that this develops a condition in which the springs at the front of the seat are 125 much stiffer than those toward the back, and the intermediate springs are of progressively lower tension or stiffness from adjacent the front to adjacent the rear springs. Consequently, the seat as a whole is progressively less resistant to 130

a load from the front toward the back of the seat.

When the article, such as a chair, is occupied, the major portion of the weight is toward the back of the seat, the portion of the seat in which the springs have the lower tension. Consequently, this portion of the seat yields more readily than the portion toward the front so that the seat will assume a generally downward and rearward tilt which tends to throw the occupant toward the back of the article or chair into a comfortable position. Immediately, however, that the occupant rises from a chair, all of the springs expand to the full extent permitted by the tie cords and thus restore the top of the seat to its normal position in a horizontal plane.

It is preferable to use rigid upholstery spring supporting members since such avoid possibility of the sagging of the central portion of the seat, due to the stretch, tearing or loosening of the burlap webs, if such be used. Furthermore, the use of such rigid supporting members permits the adaptation to a seat, constructed to afford a graduated resiliency as described, of spring suspension means for the support, which means comes into play only when, under excessive loads the upholstery springs 18 are tensioned to a degree to overcome the tension of the suspension springs 16. If it were not for the use of such suspension springs, an excessive load upon the seat would fully collapse the springs toward the back of the seat particularly, so that an occupant would be brought to a dead stop with a sudden jar when rigid spring supporting means are employed. This is known as "striking bottom".

The use of the springs 16 prevents this condition. If both front and rear suspension springs be employed there is a relatively greater cushioning action of the rear springs, although both sets of springs 16 may expand.

I have found, in actual practice, that the hinging of the rigid supporting member to the front rail affords a very comfortable seat without likelihood of any of the springs ever striking bottom. This is due to the fact that there is seldom any material load placed upon the springs toward the front of the article.

The use of the fittings shown in Fig. 4 is for the purpose of permitting a rapid attachment of the rigid spring supporting member to this front rail, and also to permit the mounting of the springs upon the slats or other rigid supporting member before assembling same in the seat structure.

The arcuate tongues prevent any possibility of the forward ends of the slats being disengaged from the plate carried by the front rail, and yet these plates may be secured in position upon said front rail before the rail is assembled in the chair or sofa frame.

The construction and arrangement of parts in the seat is such as to not only promote comfort of the user, but also to facilitate the assembling of the seat structure in the article of furniture.

When so assembling, the springs 16 are attached to the supporting member therefor. After being so attached, the supporting member is mounted in relation to the front and rear rails of the seat structure by either hooking the upper ends of the springs 16 in the fittings 15, or by passing the arcuate tongues 26 through the openings 24 of the plate 21, and then attaching the springs 16 at the rear of the slat to the fittings 15 carried by the rear rail 12.

When the rigid supporting members are thus assembled within the seat frame, all of the springs

18 are expanded to their full extent. Thereafter tie cords are affixed to the spring and to the rails 11, 12, 13 and 14 in the usual manner, all of the springs being compressed so as to bring the tops thereof on substantially the same horizontal plane as the top of the front rail 11.

Aside from the mounting of the springs upon the slats or other rigid supporting means, prior to the assembly of this means and the attached springs before mounting said rigid supporting means upon the rails 11 and 12, the assembly practices are the same as with an ordinary furniture seat. Notwithstanding this, the conditions in the seat as a result of these practices will be entirely different from those of the ordinary seat resulting in that graduated resiliency in the seat structure as a whole heretofore referred to.

The springs 18 are of the usual construction, and the finished article of furniture, excepting for the downward tilt of the side rails 13 and 14 and the lowering of the back rail 12, has the appearance of the ordinary piece of furniture of the same class.

It is not my intention to limit the invention to the precise details of construction shown in the accompanying drawing, it being apparent that such may be varied without departing from the spirit and scope of the invention.

The employment of spring sustained, rigid spring supporting members is highly desirable as affording additional ease and comfort in the use of the article of furniture. The use of webbing is undesirable because of the additional labor of installation and the liability of such webbing to become disarranged with hard use of the furniture.

Having described the invention, what I claim as new and desire to have protected by Letters Patent, is:—

1. A furniture seat embodying therein the combination with the frame of an article of furniture, of upholstery spring supporting means downwardly inclined from adjacent the front to adjacent the back of the frame, a plurality of upholstery springs mounted on said supporting means, yieldable suspension means for said supporting means to permit said supporting means to descend when the load upon said upholstery springs is sufficient to overbalance the action of the suspension means, and means tensioning said upholstery springs and bringing the tops thereof to a substantially horizontal plane, whereby said upholstery springs, from adjacent the front to adjacent the back of the seat, will be of progressively lower tension.

2. A furniture seat embodying therein the combination with a frame for an article of furniture having bars at the back and front thereof, of rigid upholstery spring supporting means downwardly inclined from adjacent the front to adjacent the back of the frame, a plurality of upholstery springs carried by and connected with said supporting means, and means tensioning said upholstery springs and bringing the tops thereof to a substantially horizontal plane, whereby said upholstery springs, from adjacent the front to adjacent the back of the seat, will be of progressively lower tension.

3. A furniture seat embodying therein the combination with a frame for an article of furniture having bars at the back and front thereof, of rigid upholstery spring supporting means downwardly inclined from adjacent the front to adjacent the back of the frame, a plurality of

upholstery springs carried by and connected with said supporting means, vertically extending suspension springs connected with said means and with the frame, whereby said means are permitted to descend when the load upon said upholstery springs is sufficient to overcome the tension of said suspension springs, and means tensioning said upholstery springs and bringing the tops thereof to a substantially horizontal plane, whereby said upholstery springs, from adjacent the front to adjacent the back of the seat, will be of progressively lower tension.

4. A furniture seat embodying therein the combination with a frame for an article of furniture having bars at the back and front thereof, of rigid upholstery spring supporting means downwardly inclined from adjacent the front to adjacent the back of the frame, a plurality of upholstery springs carried by and connected with said supporting means, means pivotally connecting said supporting means to the front of the frame, vertically extending expansion springs connected with said supporting means and with the back of the frame, whereby the portion of said supporting means adjacent the back of the frame will descend when the load upon said upholstery springs is sufficient to overcome the tension of said suspension springs, and means tensioning said upholstery springs and bringing the tops thereof to a substantially horizontal plane, whereby said upholstery springs, from adjacent the front to adjacent the back of the seat, will be of progressively lower tension.

5. A furniture seat embodying therein the combination with a frame for an article of furniture having bars at the back and front thereof, of rigid upholstery spring supporting means downwardly inclined from adjacent the front to adjacent the back of the frame, a plurality of upholstery springs carried by and connected with said supporting means, a metal plate for attachment to the front of the frame, having a central tongue adapted to pass thereunder and engage same and, an oppositely projecting flange having openings therethrough and its edge downwardly turned, a metal fitting for attachment to said rigid supporting means having an upturned tongue for engagement with the end of said means, and arcuate tongues adapted to pass through the openings in and pass below and across the downturned edge of said flange, vertically extending expansion springs connected with said supporting means and with the back of the frame, whereby the portion of said supporting means adjacent the back of the frame will descend when the load upon said upholstery springs is sufficient to overcome the tension of said suspension springs, and means tensioning said upholstery springs and bringing the tops thereof to a substantially horizontal plane, whereby said springs, from adjacent the front to adjacent the back of the seat, will be of progressively lower tension.

6. A furniture seat embodying therein a frame having a front rail, a rear rail set upon a lower horizontal plane than said front rail, and rearwardly and downwardly inclined side rails, rigid upholstery spring supporting means connected with said front rail and with said rear rail respectively, and extending upon an incline from said front to said rear rail, a plurality of upholstery springs carried by and connected with said supporting means, and means tensioning said springs and bringing the tops thereof to a substantially horizontal plane, whereby said upholstery springs, from adjacent the front to adjacent the back of the seat, will be of progressively lower tension.

7. A furniture seat embodying therein a frame having a front rail, a rear rail set upon a lower horizontal plane than said front rail, and rearwardly and downwardly inclined side rails, rigid upholstery spring supporting means extending from said front rail toward said rear rail upon an incline, a plurality of upholstery springs carried by and connected with said supporting means, vertically extending suspension springs between said supporting means and said frame, whereby said supporting means are permitted to descend when the load upon said upholstery springs is sufficient to overcome the tension of said suspension springs and tie cords connected with the various upholstery springs and with said rails respectively, whereby said upholstery springs are tensioned and the tops thereof are brought upon substantially the same horizontal plane, and said upholstery springs from adjacent the front to adjacent the rear rails will be of progressively lower tension.

8. A furniture seat embodying therein a frame having a front rail, a rear rail set upon a lower horizontal plane than said front rail, and rearwardly and downwardly inclined side rails, rigid upholstery spring supporting means extending from said front rail toward said rear rail upon an incline, a plurality of upholstery springs carried by and connected with said supporting means, means pivotally connecting said supporting means to said front rail, vertically extending suspension springs connected with said supporting means and with said rear rail, whereby said supporting means are permitted to descend when the load upon said upholstery springs is sufficient to overcome the tension of said suspension springs and tie cords connected with the various upholstery springs and with said rails respectively, whereby said upholstery springs are tensioned and the tops thereof are brought upon substantially the same horizontal plane, and said upholstery springs from adjacent the front to adjacent the rear rails will be of progressively lower tension.
